AUTOMATIC SELECTING AND LOADING
DEVICE

Sillas A. Strickland, Detroit, Mich.

Application December 7, 1931, Serial No. 579,641

37 Claims. (Cl. 209—75)

This invention relates generally to assorting mechanisms, and relates more particularly to mechanisms designed to assort articles of an elongated type, such for instance, as the blanks used in the production of taper rollers for use in bearings, this being the particular service of the invention as disclosed, although it is obvious that the mechanism may be employed for the assorting of other articles or objects.

10 In taper roller bearing structures, aside from the question of the angle of taper—which can be provided approximately when the blank is being formed—the question of the length of the roller and of its maximum diameter are of the greatest importance, since upon these depend the proper operation of the bearing itself. The bearing deals with both load and thrust conditions and hence the question of the amount of advance of the roller in the thrust direction determines the 15 character of activity of the particular roller in the bearing assembly.

It is possible to take care of small variations in both dimensions during the final grinding operations, but where the operations are based 25 on high production conditions, material variations in either or both dimensions could materially affect the output, since the grinding mechanisms could not take care of such large variations and retain the production capacity 30 that is essential under such operations.

As a result, it is desirable that the blanks which are to be used should be tested as to both dimensions in order to eliminate the delivery of widely-varied blanks to the grinding mechanisms. This is desirable since the blank-production mechanisms, also operating under large 35 production conditions, cannot produce blanks which are exactly similar as to dimensions, etc., at all times.

40 The present invention is designed to meet these conditions, and is generally arranged relative to one of the grinding mechanisms so that the accepted output of the testing mechanism will be delivered at the proper feeding position 45 for the grinding mechanism.

The general cycle of testing operations used in the invention is approximately as follows: The blanks, supplied to the hopper as a mass, are segregated into a succession of individual rollers 50 travelling endwise to the first-test station. They are then moved laterally in such station enroute to a delivery point of the station—two points being provided, one for the blanks which do not meet the test and the other for the accepted 55 blanks. During the lateral travel, the blanks

are tested for length, those of the proper length being delivered to the acceptance discharge point, while those which are over or under the proper length, are passed to the discard discharge and eliminated from the apparatus. The accepted blanks then pass to a second station—still travelling endwise and without regard to which end of the roller is in advance—in which station the rollers are presented to a testing support arranged in such manner that while on the support the latter supports the roller intermediate the roller ends. As a result of this type of support, the small ends can enter but the large ends cannot pass. Consequently, rollers which are presented large end first cannot pass into the support and are temporarily rejected and later reversed end for end and again presented to the support. Blanks which are undersized in the diameter dimension will not be retained by the support, and are thus eliminated from the apparatus. The advance of the support toward the delivery position carries the succession of accepted blanks—with the blanks uniformly positioned as to end relationships—to a simple mechanism for tilting the 25 blanks to enter the discharge conduit en route to the grinding mechanism with the blanks travelling endwise, so that all blanks are similarly presented to the grinding mechanism feed control.

30 The apparatus itself carries protective structures which prevent overloading of the mechanisms. For instance, if the delivery is too rapid for the capacity of the grinding mechanism, the feed of blanks to the first testing station is stopped temporarily; should this be insufficient to eliminate overloading, the support operation of the second station is rendered inactive temporarily, to permit the accumulation to be dissipated. The presence of these permits the assorting apparatus to operate under higher speed conditions, due to the fact that the successive elimination of discards provides a percentage effect relative to the accepted blanks, so that the speed of the assorting apparatus can be arranged 40 to ensure an average delivery of accepted blanks to approach capacity conditions of the grinding mechanism—the protective devices serve to meet the conditions where the percentage of discards is less than the average.

50 From this it will be understood that the invention is designed to permit of the production of taper rollers under large production conditions, by initially providing for an approximate sizing action provided by the assorting mechanisms, to 55

discard such blanks as are not usable for the particular purpose. Since the apparatus tests a greater number of blanks than are being ground per unit of time, it can be understood that the 5 blank-forming mechanisms can be operated at speeds sufficient to maintain the mass supply for the assorting mechanism.

To these and other ends, therefore, the nature 10 of which will be understood as the invention is hereinafter described, said invention consists in the improved constructions and combinations of parts, as more fully disclosed in the following description, illustrated in the accompanying drawings, and more particularly described in the appended 15 claims.

The invention is fully disclosed by way of example in the following description and in the accompanying drawings, in which—

Figure 1 is a vertical section of the machine; 20 Fig. 2 is a detail elevation of the machine in a plane at right angles to that of Figure 1 and showing the selector mechanism in section;

Fig. 3 is a detail plan view with certain of the upper structure removed;

25 Fig. 4 is a side elevation, partly in section; Fig. 5 is a section on the line 5—5 of Figure 2;

Fig. 6 is a section on the line 6—6 of Figure 2;

Fig. 7 is a detail section in the same plane as Figure 2, showing the action of the selector mechanism on a roller of proper dimensions;

Fig. 8 is a similar section showing the action of the selector mechanism in rejecting a member that is too short;

Fig. 9 is a similar section showing the action 35 of the selector mechanism in rejecting a member that is too long;

Fig. 10 is a detail plan view with certain of the upper structure removed;

Fig. 11 is a detail end view;

40 Fig. 12 is a detail perspective view of the follower in the selector mechanism; and

Fig. 13 is a detail elevation of a modified construction.

Reference to these views will now be made by 45 use of like characters which are employed to designate corresponding parts throughout.

As shown in Figure 1, the frame structure of the machine includes a base 1 on which is mounted a hollow column 2 having an enlarged upper end 3. A cover plate 4 is secured upon the upper end and in turn has secured thereto a partition 5 for a purpose which will presently appear. Upon the plate 5 is mounted a housing or body 6 having a flared upper end 7.

55 Directly beneath the flared end 7 is fixedly mounted a liner 8 presenting a conical inner surface approximately in alignment with the inner surface of the flared end 7. Directly beneath the member 8 is rotatably mounted a conical member or hopper 9 having a downwardly extending sleeve portion 10. The upper end of the sleeve is mounted in a bearing 11 within the body 6. At a lower point, the sleeve portion 10 carries a worm gear 12 keyed thereto at 13 and meshing with a driving worm 14, journalled in the body 6 and driven by any suitable means. The previously mentioned partition 5 carries another bearing 15 for the sleeve 10 and also carries packing material 16 engaging the sleeve so that the body 6 may be packed with lubricant between the bearings 11 and 15 without danger of leakage to the lower parts of the mechanism.

Upon the flared end 7 is secured a top plate 17 which in turn carries a depending stud 18 lying 75 in the axis of the funnel or hopper formed by the

parts 7, 8 and 9. The member 10 has an enlarged conical lower end 19 entering the apex of the member 9 and obstructing the passage 20 which connects the member 9 with the sleeve 10. In the member 10, however, is formed a 5 groove 21 (Figure 4) forming a restricted passage for admitting material from the hopper to the opening 20.

An arm 22 is fixed to the flared end 7 and extends into the hopper as may also be seen in 10 Figure 4. The rotating member 9 carries a screw-thread 23 which, in conjunction with the fixed member 22, agitates the material in the hopper.

The machine as illustrated herein is adapted 15 more particularly for the feeding of tapered bearing rollers which are thrown into the hopper by any suitable means. The cross-sectional area of the passage 21 is slightly greater than the similar area at the maximum diameter of the rollers but less than the area of a longitudinal section of the 20 roller, so that the rollers will be delivered to the opening 20 only in lengthwise position for endwise movement.

A tube 24 has its lower end set in the bottom of the enlarged top 3 and extends into the sleeve 25 10. The lower end of the tube is fixed in position by a nut 25 screwed against the same and having a bore 26 registering with the inner wall of the tube 24.

The column 2 has a flange 27 to which is bolted 30 an outwardly extending bracket 28. The bracket in turn supports a block or body 29 extending beneath the nut 26. The member 29 has a longitudinal passage 30, the upper side of which is enlarged to form a guideway 31, as shown more 35 clearly in Figures 5 and 6 for a purpose which will presently appear. Finally, a member 32 is secured upon the body 29 at one end thereof and has a bore 33 forming a prolongation of the bore 26 and extending to the passage 30 as may be seen 40 in Figures 2, 7, 8 and 9. The member 32 has sight holes 32' through which the pieces may be seen as they drop through this member.

In the passage 30 is mounted a slide 34 in the form of a hollow sleeve and preferably rectangular in cross section. The upper wall of the slide is formed with an opening 35 adapted to register with the bore 33 in one position of the device, as shown in Figure 2. The side walls of the slide are notched or shouldered at 36 for a purpose which will presently appear. In the bottom wall of the slide is formed another slot 37 offset somewhat from the slot 35.

A plunger 38 also of hollow construction is 55 slidably mounted in the slide 34 and has an operating stem 39 passing through an end of the slide. Directly adjacent the stem, the plunger has an open top adapted to communicate directly with the bore 33 in certain positions of the parts. The bottom of the cylinder has an opening 40 adapted to register with the slot 35 and with the bore 33 when the parts are in the retracted position shown in Figure 2. Adjacent the slot, the plunger is built up to form a partition or abutment 41 and from that point is extended through the open end of the slide and is formed with a depending stop lug 42.

The free or exterior end of the stem 39 carries a fixed stop collar 43 adjacent which is a 60 slideable sleeve 44. Near the slide 34, the stem 70 39 has a cup 45 secured thereto by a pin 46. A coil spring 47 surrounds the stem between the members 44 and 45. An oscillatory arm 48 is joined to the slideable collar 44 and is actuated by a means presently to be described, thereby con- 75

stituting the actuating means for the stem 39 through the medium of the spring 47 and cup 48. Another spring 49 surrounds the stem 39 between the cup 45 and the adjacent end of the slide. This spring is lighter than the spring 47, so that on inward movement of the arm 48, the spring 49 is first compressed until the cup 45 engages the slide. In this movement, the plunger moves relatively to the slide, and on continued inward movement of the arm 48, both the plunger and slide move together, there being however a resilient drive connection between the arm and the cup.

The bottom wall of the member 29 has a discharge opening 50 communicating with the passage 30 and offset somewhat from the bore 33. This outlet is so positioned as to communicate with the bottom slot 37 of the slide during the initial movement of the latter as shown in Figures 2, 8 and 9. Adjacent the outlet 50 is another discharge outlet 51 also communicating with the passage 30 and offset a greater distance from the bore 33 to register with the slot 37 at a later interval in the inward movement of the slide.

Beneath the body 29, another block 52 is secured to the bracket 28 and is formed with a trough or chute 53 in communication with the outlet 50. As will presently appear, this chute receives irregular members which have been rejected by the selecting mechanism. The block 52 is formed with another chute or passage 54 registering with the outlet 51 and adapted to receive perfect members from the selecting mechanism and convey them to a loading or feeding device.

A plate 55 is slidably mounted in the guideway 31 and has an upstanding portion 56 normally abutting the member 32 (Figs. 2 and 4). The base of the piece 56 has a pair of lugs 57 extending into a notch 58 cut in the member 32 at the bore 33. The space between the lugs is sufficient to receive one of the elements delivered into the bore from the sleeve 24. A cross piece 59 is laid over the sliding plate 55 and has its ends bolted as at 60 (Figure 3) to retain the plate in the guideway 31. An angular member 61 is secured to the piece 56 and is formed at one end with a cam surface 62 as may be seen in Figures 3, 4 and 6. In the block 29 is mounted a stop pin 63 adapted to enter the passage 30 but normally retracted therefrom by a spring 64 engaging a head 65 formed in the pin. This head normally engages the cam surface 62 as shown in Figure 3.

In the upstanding member 56 is slidably mounted a plunger 66 (Figure 12) held under pressure against the slide 34 by a spring 67. The lower edges of the plunger lying transverse of the slide are beveled intermediately as at 68, so that the corners 69 remain intact. The lower face of plunger 66 normally rests in a notch 70 on the top of plunger 38 over abutment 41.

The members to be passed through the selecting mechanism may be assumed to be tapered bearing rollers delivered from the hopper to the bore 33 in the manner already described. Each end of such a member has a small projection in the center thereof as the result of the machine operations employed in its manufacture. To accommodate these projections, the bottom surface of the plunger 66 has a small groove 72 communicating with a similar groove 71 in the underside of the slide plate 55. To accommodate the lower projection, the upper face of the bottom wall of the hollow slide 34 has a short groove 72

adjacent the slot 37. A rod 73 extends from the slideable member 56 slidably through the back of the member 32 as shown more clearly in Figure 3. The outer end of the rod carries a stop collar 74, and the external part of the rod is surrounded by a spring 75 bearing against the collar and the fixed member 32, thereby drawing the slideable member against the fixed member.

The operation of the selector mechanism thus far described is as follows:

The selection during this stage is based on the length of the article (a taper roller bearing, for instance), the purpose being to select those of a proper length and to reject those which are either too short or too long. The slot 21 has forced the individual delivery of the rollers in an endwise direction from the mass in the hopper, but without attempting to force delivery small end first, or vice versa, the only condition being that they advance endwise through the aligned channels 20 leading to bore 33.

The start of the selection as to length begins with the position of the parts in Fig. 2. In this position the slots 35 and 40 are aligned with slot 33, so that the roller delivered to bore 33 will drop downward until it comes to rest on the upper face of the bottom of the slide 34. In such position, a roller of the proper length will be located in both of the slots 35 and 40 and be in position to be advanced laterally of the roll 30 axis by movements of arm 48. With a roller of the proper length, its top will be sufficiently above the bottom of notch 76 as to cause it to be effective with a cam face 68 but remain clear of piece 56. If the roller is too short, its top surface will not reach to a height sufficient to engage and actuate plunger 67. If the roller is too long, its upper face will extend above the bottom of piece 56.

Assuming the roller to be of the proper length, a movement of arm 48 toward the right in Fig. 2 will cause both slide 34 and plunger 38 to advance, resistance to advance being insufficient to compress either of the springs 47 and 49, so that the parts initially travel as a unit. As the advance proceeds, the slide advance closes slot 50 ahead of the positioned roller, so that the advance of the latter does not open slot 53 for the roller. The advance brings the roller to plunger 66, the top of the roller engaging the cam face 68 and raising the plunger 66 so that the corners of the latter are raised out of engagement with the notch 36 of slide 34, thus permitting the latter to continue its advance. The advance then continues until slide 34 engages stop 71, a position which leaves slot 37 aligned with slot 51. With the advance of the slide 34 thus stopped, the continuance of the advance of arm 48 acts to compress spring 49 during the continued advance of plunger 38, until cup 45 contacts with the end of slide 34, at which time slot 40 is also aligned with the slots 37 and 51, thus permitting the roller to pass into slot 51 for further action. Figure 7 illustrates the positions of the parts as the roller is approaching its position of discharge through slot 51.

Assuming that the roller is too short, the initial advance of slide and plunger from the position of Figure 2 will bring the roll to its position relative to cam 68. But in this case, the height of the roller is not sufficient to raise plunger 66, with the result that shoulders 38, engaging plunger 66, prevent further advance of the slide 34. At this time, slot 37 is still aligned with slot 50, and hence the further independent advance of 75

plunger 38 during which spring 49 is being compressed, will bring slot 40 into alignment with slot 37 when cup 45 becomes engaged with the end of the slide, thus placing the parts in position to discharge the roller, the discharge, however, being through slot 50 and into the rejected group. Figure 8 shows the position of the parts at the latter time. Further travel of arm 48 to complete its cycle simply compresses spring 39, since the locked slide 34, with cup 45 in engagement therewith, prevents further advance of rod 39.

When the roller is too long, the immediate action is different. The height of the roller in such case does not permit its top to pass the bottom of piece 56, so that the upper portion lies opposite a face 82 of this piece. Hence, the advance of arm 48 not only produces the advance of the slide 34 and plunger 38, carrying with them the roller, but the advance of the roller carries with it the slide 55 with the parts carried thereby, this movement continuing until the pin 63 is advanced into the path of the slide 34 by the coaction of cam 62 with head 65. At this time slot 37 is in alignment with slot 50, and under the continued advance of plunger 38, during which spring 49 is being compressed slot 40 is brought into alignment with slot 37 at which time the roller drops out through slot 50 into the rejected group. Figure 9 illustrates the positions of parts during the latter part of this cycle of operation. The movement of the slide 55 is permitted by the yielding of spring 75, the latter acting to return slide 55 to its normal position when the roller has been discharged, the return movement of arm 48 returning the slide 34 sufficient to carry notches 36 to their normal position. Should the springs 47 and 49 prove insufficient to shift the slide 55 a sufficient distance to bring slot 40 into alignment with slot 37 in presence of the resistance of spring 75, a handle 83 on slide 55 will serve to permit manual advance of this slide until cup 45 engages the slide.

As will be readily understood, in each of the operations there is an initial concurrent advance of slide 34 and plunger 66, during which spring 49 is not affected followed by a selective action on the slide to determine the length of the advance of the latter, the selection being made by the length of the roll, the action being made manifest by the activity or inactivity of plunger 66, in case of the proper length of roller or a short roller, and by the advance of slide 55 out of its normal position where the roller is too long. In each instance, the advance of the slot is stopped with its slot 37 in alignment with one or the other discharge slot or outlet, and in each instance, the plunger 38 then continues its advance until slot 40 becomes aligned with slot 37, this being controlled by the contact of cup 45 with the end of the slide to limit the plunger advance, a limit that is fixed by stopping the advance of slide 34 in each of the operations described, the plunger then continuing to advance to bring slots 40 and 37 into alignment, the continued advance of the plunger being permitted by the compression of spring 49.

As will be understood, the articles or blanks which pass out through slot 50 and chute 53 are the rejected ones and are thus passed permanently out of what may be termed the supply. Those which are delivered into chute 54 through slot 51 are those which have been accepted and continue onward in the general cycle as the supply. In other words, the blanks from the mass in the hopper pass to a testing point in-

dividually the latter forming a supply; at this testing point, the blanks are tested as to length, and only those of the proper length characteristic continue onward as the supply, the rejected ones passing out of the path.

The test as to length is not the only one that is needed. The blanks are generally shaped to an approximately uniform dimension, but under production conditions there is necessarily no assurance of exactness and similarity in dimensions of a succession of blanks. Hence, it can be understood that there may also be variations in the diameter characteristic of the blank, thus requiring a testing of each blank in this respect in order to eliminate those which may not come within certain dimensional characteristics suitable for the production of the finished roller. Since the blank is subsequently ground to its exact dimensions diametrically, a small range of variation is permissible in the tests in this dimension.

The initial test in this respect is made at the time the blanks pass from the hopper into passage 21, it being obvious that oversize blanks diametrically will not pass through the passage 21. The latter may therefore be considered as presenting the maximum diameter characteristic. Obviously, there may be blanks which are undersize in this dimension. The latter would not provide for the proper size finished roller, and hence must be taken from the supply. Since there is a variation permitted, advantage is taken of this fact to provide a testing characteristic by suitable mechanism which not only will serve to eliminate the undersize blanks but will automatically deliver the accepted blanks with the same selected end in advance, regardless of which end may have been in advance during the previous travel of the blank through the apparatus. Briefly stated, this result is obtained by the manipulation of the blank.

The fundamental feature in this manipulation is the supporting of the blank by a carrier structure in which the support is provided by two opposing faces spaced a distance sufficient to permit the smaller end of the roller to pass therethrough but which will prevent the larger end passing, thus setting up the characteristic of a support for the roller intermediate its ends. A support of this type enables the assembly to provide the double duty of eliminating undersize rollers and to arrange successive rollers to advance with the same end in advance. This will be understood from the fact that unless the roller approaches the space between the faces with the small end first it will be unable to enter the space unless it be an undersized roller. Hence, the roller approaching large end first will be rejected, and the undersize roller will pass completely through the space and be eliminated. The end-rejected roller is then turned end for end by the operation of the mechanism and thus again approaches the space with its small end first and enters the space to be properly supported.

The mechanisms for producing the latter results will now be described:

In the column 2 is journalled a shaft 85 in bearings 86. The upper end of this shaft carries a gear 87 meshing with a smaller gear 88 on the sleeve 10. The speed imparted to the shaft 85 may obviously be varied by changing the sizes of the gears 87 and 88 on removal of the upper structure.

The base member 1 carries a ball bearing 89 in one of its sides, and in this bearing is fitted 75

- a sleeve or bushing 90 having at one end a thrust nut 91 engaging the bearing. A part of the bushing 91 is surrounded by a sleeve 92 terminating in a pair of opposed forks 93 for a purpose which will presently appear. On the sleeve 92 is mounted a bevel gear 94 meshing with another bevel gear 95 on the lower end of the shaft 85. The gear 94 is pinned to the sleeve 92 as at 96. A collar 97 is inserted between the bearing 89 and the adjacent ends of the members 92 and 94. A shaft 98 passes through the bushing 90 and carries a transverse pin 98 which is normally received in the forks 93. A housing 99 is secured to the same side of the base 1 and contains a spring 100 which exerts a thrust on the bearing 89 and therefore against the sleeve 92 and gear 94. A smaller spring 101 bears against the bushing 90 and a collar 102 on the shaft, thereby drawing the pin 98 into the forks 93.
- 10 The bushing 90 is part of a solid shaft 103 which passes through a ball bearing 104 in the opposite side of the base. The shaft has a slot 105 which receives the pin 98. A nut 106 is mounted on the shaft 103 and bears against the bearing 104.
- 15 The thrust delivered by the spring 100 to the sleeve 92 is transmitted to the shaft 103 at the shoulder 107 thereof and thence to the bearing 104 through the nut 106. Thus, the slack in both bearings, especially the bearing 104, is taken up.
- 20 A plate 108 is secured to the side of the base and around the shaft 103 by bolts 109. The plate is fitted over a hub member 110 secured to the base 1 and may be adjustably spaced from the base by means of lock nuts 111 on the bolts 109.
- 25 The plate 108 has a laterally projecting flange 112. Adjacent the plate is a hub 113 mounted on the shaft 103 and extending partly into the hub 110. To the member 113 is secured a plate 114 having a flange 115 directed towards the flange 112 and forming a space 116 therewith. The confronting edges of the flanges 112 and 115 are beveled inwardly as at 117.
- 30 The chute 54 which receives the members 78 of proper length leads to the disks 108 and 114 and is adapted to discharge into the space 116 therebetween. This space however is so adjusted as to receive the narrower ends of the members but not the wider ends. Consequently, those members which fall through the chute and do not present their smaller ends to the space 116 are not immediately admitted.
- 35 The bottom plate 120 of the chute (Figure 11) has a slot 121 in which is pivotally mounted a boss 122 at the end of the chute. From the boss 55 extends a finger 123 into the chute and adapted to engage members 78 therein. A lever 124 also extends from the boss inwardly below the bottom of the chute. A spring 125 draws the lever towards the chute, and the movement of the lever in this direction is limited by a stud 126 engaged by a stop pin 127 also extending from the boss 122. The outer or rotary plate 114 is formed with a series of radial slots 128 into which may be adjustably mounted one or more cam members 129 projecting beyond the periphery of the plate in a manner to swing the lever 124 outwardly in passing the same. When the lever returns under the action of the spring 125, the finger 123 strikes a member 78 as shown in Figure 13 and thus changes the position of the members in the bottom of the chute 54. By this means, the members 78 not initially presenting their narrower ends to the space 116 may be turned about so that they can enter the space.
- 40 On the base 1 is secured a member 130 which

extends upwardly at an angle into the space between the plates 108 and 114 alongside the outlet of the chute 54. This member has a V-groove 131 and further has a pair of plates 132 fixed to its sides and extending into close proximity to the flanges 112 and 115. If the larger end of a piece is too narrow to be retained in the space 116 by the flange 112 and 115 it will drop to the member 130 and be discharged from the machine. The fixed flange 112 has a clearance adjacent member 130 to permit the latter to readily pass (see Fig. 13).

To the base 1 is also secured a trip member 133 extending into the space between the plates and terminating adjacent the upper end of the member 130. The upper edge of the trip member is rounded as at 134. The members 78 that remain suspended between the plates are rolled by the rotary plate 114 until their lower ends engage the trip 133, as shown in Figure 2, whereupon they are raised and upset in riding over the curved edge 134 to place their larger ends foremost.

Plates 135 are secured to the sides of the member 133 exteriorly of the plates 108 and 114 in a manner to form a chute for the members 78 as they drop off the edge 134. From this chute, the members fall through an inclined tube 136 and are passed through a timed escapement mechanism 137 to grinding apparatus 138 as shown in my copending application, Serial No. 328,328, filed December 26, 1928.

A bracket 140 extends from the block 52 and serves as the bearing for a shaft 141 (Fig. 4) to which the lower end of the arm 48 is secured. From this shaft extends also another arm 142 having at its lower end a roller 143 lying in the path of the cam member or members 129. Consequently, the arm 48 is actuated as often as the lever 124. A lug 144 extends from the shaft 141 and is drawn towards the member 52 by a spring 145. The action of the spring is limited by the engagement of the end of the wall of the slot 76 against the corners 68 of the plunger 66.

A bell crank 146 is pivoted between the plates 135 and carries at one end a stud 147 adapted to enter the tube 136. The other end of the bell crank is articulated to the arm 48 by a link 148. If the members 78 pile up in the tube 136 as far as the stud 147, the stud will rest on one of the members and, through the bell crank 146, will throw the arm 48 inwardly to shift slot 35 out of its receiving alignment sufficient to prevent feed of blanks; the movement will also draw the roller 143 away from the periphery of the disk 114. In this position, the roller 143 is either not engaged by the cam 129 at all or insufficiently to perform a full operative stroke of the slide 34 and plunger 38. Under these conditions, delivery of members to the plates is interrupted, and excessive accumulation of members in the tube 136 and chute 133 is prevented.

If for any reason the rotary disk 114 should become jammed and the shaft 103 locked, the drive on the sleeve 92 causes the forks 93 to ride off the pin 98 of the shaft 88, the latter being moved towards the shaft 103 against the tension of the spring 101. The shaft 88 has a pair of spaced collars 150 and 151 at its outer end, and a locking finger 153 is pivoted on the housing 99 near the collars. If it is desired to disconnect the sleeve 92 permanently from the shaft 88, the latter is moved inwardly until the pin leaves the forks 93. At this time, the space between the collars is directly in line with the member 153 which may now be swung into this space.

In the modification shown in Figure 13, the base member 155 of the discharge chute 156 leading to the grinder has its upper end relieved at 157 in order to afford no interference with the suspended members 78 as they are moved towards the chute. In other words, the members 18 are not tripped in the same manner as in the previously described construction. In the present instance, the trip member is in the form of a piece 158 fastened to the upper part of the chute 156 in a manner to be engaged by the tops of the members 78. Consequently these members ride down the chutes with their smaller ends foremost.

15 As will be understood, the arrangement of the length-testing and diameter-testing mechanisms is such as to set up what may be termed a pre-determined standard of dimension. For instance, a blank which will pass beneath the member 57 and which will raise the plunger 66 to inactive position, would be a blank whose length dimension was within this predetermined standard, since only a blank capable of meeting these conditions would permit slide 34 to advance to the 20 position of Figure 7. Similarly, the width dimension of the space between the supporting faces of disks 108 and 114 can provide such standard.

25 It will also be understood that the various channels, etc., reaching from the hopper to the discharge chute 136 form a travel path for the blank, such path obviously including the path taken by the blank while in the testing mechanisms. In this path the blanks are normally positioned to move in an endwise direction, but in the 30 testing portions of the path the movements of the blank are transverse to such endwise direction; but such transverse movement does not change the general endwise condition, so that when released from the testing mechanisms the 35 blank continues to travel in such endwise relation.

40 And in the operation of the length-testing mechanism, it will be readily understood that the two elements—the slide 34 and plunger 38, travel 45 both in unison and relatively to each other, the length of the relative movement being similar in all cases, due to the fact that this length is controlled by the cup 45. The length of the movement in unison, however, varies. With the 50 short roller, the length is the distance travelled by the slide until 36 contacts with plunger 66; with the long blank, the length is determined by the contact of the slide with stop 63; and with the standard length it is determined by the contact of slide 34 with stop 77. Hence, the length 55 of the slide movement is varied, and it is this variation that permits discharge of the blank through the proper outlet, since it is this that controls the position of opening 37, the purpose 60 of the relative movement being to bring opening 40 of the plunger 38 into proper relation with opening 37 to permit the passage of the blank; the length of the relative movement can thus be the same in all cases. The length-testing operation is thus primarily one which determines the 65 point of beginning of the relative movement, and this point is determined by the blank and its travel, so that the blank practically tests itself.

70 From the above it will be readily seen that the general arrangement shown not only provides for a segregation of rollers from a mass to provide a succession of rollers which are individually tested to determine their suitability for further operation to complete the rollers, but that the 75 arrangement is such as to provide for a number of

positive advantages in operation. A few of these will be referred to.

It is unnecessary to enlarge upon the advantage of eliminating unsuitable blanks before the roll-grinding station is reached. Such elimination 5 limits the work of the roll grinder to action on rollers that are capable of being used, thus saving the time and expense of grinding an unsuitable roller, and eliminates the necessity of carefully measuring and inspecting the completed roll 10 in its length and diameter dimensions. In addition, assuming an approximate percentage of rejected rollers, it can be understood that the assorting apparatus can be speeded up relative to the grinding mechanism, so that the latter will 15 be able to work at approximate capacity. Should the percentage of unfit blanks be less during a period, the control mechanism brought into action by the element 147 will prevent choking of the grinding mechanism.

20 The feed of the roller is endwise of the roller with the length tests provided by lateral or side-wise movements of the roller. In this way the roller is prepared initially for the diameter test and the upsetting action, if the latter be required. 25 Consequently, the size testing and positioning of the rollers as to delivery can all be done at practically two points or stations of the apparatus, one of these testing as to length and the other as to diameter and to position. As a result, there is 30 no need of an attempt to force delivery from the mass with a particular end of the roller in advance, making it a simpler and more rapid operation at the start of the travel of the roller as an individual.

35 The particular arrangement of testing is also of advantage. Obviously, the tests are most advantageously made by a stage operation, since the discards of the first test need no longer be considered at the second testing station. However, by making the length test as the first stage, it permits the second test to be made by the particular method employed at the second stage, where the diameter test is actually made by the supporting mechanism which transmits the blank 45 from the chute 54 to the delivery chute, thus requiring no specific gaging structure other than the support itself. In addition, it enables the end for end upsetting of the roll for the purpose of positioning the latter without any material difficulty or a special station.

40 The stage testing as to dimensions is of advantage due to the fact that it permits the discards to be segregated into separate receptacles, one based on variations in length, and the other on 45 variations in diameter, but with the proper length. As a result, it makes it possible to utilize the discards for other operations without initially making a careful test of the discards individually, the apparatus automatically dividing the discards 50 into the two major classes.

45 By providing the test in advance of grinding, the tests can be made with less exactness conditions, since the succeeding operations are such as to correct for the small variations which the testing mechanism permits. Hence, the testing mechanism can be made more substantial and able to better resist deterioration than where the tests are to be made with extreme accuracy; in the latter case the mechanism must be able to 55 operate with complete exactness, and the attempt to operate under production conditions is more likely to produce rapid deterioration of parts and thus necessitate frequent repairs.

50 Structurally, the several mechanisms are sim- 75

- ple in character and such as are not likely to get out of order even under the onerous conditions of operations capable of meeting the conditions of production output. The machine is generally automatic in operation—this is varied only under abnormal conditions, as when it is necessary to move slide 55 manually. The specific advantages of individual structures are obvious and need not be referred to in detail.
- 10 Although specific embodiments of the invention have been illustrated and described, it will be understood that various alterations in the details of construction may be made without departing from the scope of the invention, as indicated by the appended claims.

What I claim is:—

1. In a mechanism for selecting articles of a given length, a body having a material inlet and two material outlets, one for regular and the other for irregular articles of manufacture, a hollow slide beneath said inlet and over said outlets, a plunger slidable within said slide, said slide having an intake opening adapted to register with said inlet and an outlet slot adapted to register with either of said outlets, said plunger being adapted to receive an article of material and having also a slot in its bottom adapted to register with said outlet slot, a follower under pressure and adapted to extend into the path of said slide, stop means between said follower and slide, said follower being adapted to be moved out of the path of said slide by an article of regular length received in said plunger and slide, and a yieldable driving connection between said plunger and slide, whereby the slot of said plunger may be brought into register with said outlet slot.
2. In a mechanism for selecting articles of a given length, a body having a material inlet and two material outlets, one for regular and the other for irregular articles of manufacture, a hollow slide beneath said inlet and over said outlets, a plunger slidable within said slide, said slide having an intake opening adapted to register with said inlet and an outlet slot adapted to register with either of said outlets, said plunger being adapted to receive an article of material and having also a slot in its bottom adapted to register with said outlet slot, a follower under pressure and adapted to extend into the path of said slide, stop means between said follower and slide, said follower being adapted to be moved out of the path of said slide by an article of regular length received in said plunger and slide, a permanent stop engageable by said slide when the outlet slot thereof registers with the regular material outlet, and a yieldable driving connection between said plunger and slide, whereby the slot of said plunger may be brought into register with said outlet slot.
3. In a mechanism for selecting articles of a given length, a body having a material inlet and two material outlets, one for regular and the other for irregular articles of manufacture, a hollow slide beneath said inlet and over said outlets, a plunger slidable within said slide, said slide having an intake opening adapted to register with said inlet and an outlet slot adapted to register with either of said outlets, said plunger being adapted to receive an article of material and having also a slot in its bottom adapted to register with said outlet slot, a follower under pressure and adapted to extend into the path of said slide, stop means between said follower and slide, said follower having a beveled edge engageable by an article of regular length received in said plunger

and slide, whereby said article moves said follower out of the path of said slide, and a yieldable driving connection between said plunger and slide, whereby the slot of said plunger may be brought into register with said outlet slot.

4. In a mechanism for selecting articles of a given length, a body having a material inlet and two material outlets, one for regular and the other for irregular articles of manufacture, a hollow slide beneath said inlet and over said outlets, a plunger slidable within said slide, said slide having an intake opening adapted to register with said inlet and an outlet slot adapted to register with either of said outlets, said plunger being adapted to receive an article of material and having also a slot in its bottom adapted to register with said outlet slot, a follower under pressure and adapted to extend into the path of said slide, a shoulder on said slide adapted to be stopped by an edge of said plunger and to hold the outlet slot of said slide over the irregular material outlet, said edge having a bevel engageable by an article of regular length received in said plunger and slide, whereby such an article moves the follower out of the path of the slide, and a yieldable driving connection between said plunger and slide, whereby the slot of said plunger may be brought into engagement with said outlet slot.

5. In a mechanism for selecting articles of a given length, a body having a material inlet and two material outlets, one for regular and the other for irregular articles of manufacture, a hollow slide beneath said inlet and over said outlets, a plunger slidable within said slide, said slide having an intake opening adapted to register with said inlet and an outlet slot adapted to register with either of said outlets, said plunger being adapted to receive an article of material and having also a slot in its bottom adapted to register with said outlet slot, a follower under pressure and adapted to extend into the path of said slide, a shoulder on said slide adapted to be stopped by an edge of said plunger and to hold the outlet slot of said slide over the irregular material outlet, said edge having a bevel engageable by an article of regular length received in said plunger and slide, whereby such an article moves the follower out of the path of the slide, a yieldable driving connection between said plunger and slide, whereby the slot of said plunger may be brought into engagement with said outlet slot, and a permanent stop engageable by said slide when the outlet slot thereof registers with the regular material outlet.

6. In a mechanism for selecting articles of a given length, a body having a material inlet and two material outlets, one for regular and the other for irregular articles of manufacture, a hollow slide beneath said inlet and over said outlets, a plunger slidable within said slide, said slide having an intake opening adapted to register with said inlet and an outlet slot adapted to register with either of said outlets, said plunger being adapted to receive an article of material and having also a slot in its bottom adapted to register with said outlet slot, a block slidably mounted on said body over said slide, a follower under pressure in said block, a wall portion formed with said block between said material outlet and follower and engageable by an article of excessive length received in said plunger and slide, whereby to shift said block on further actuation of said plunger and slide, means operable on shifting of said block for stopping said slide with the outlet slot thereof in register with the

irregular material outlet, means for further shifting said block, and a yieldable driving connection between said plunger and slide, whereby said plunger may be moved relatively to said slide until its outlet slot registers with the outlet slot of said slide on such further shifting of said block.

10 7. In a mechanism for selecting articles of a given length, a body having a material inlet and two material outlets, one for regular and the other for irregular articles of manufacture, a hollow slide beneath said inlet and over said outlets, a plunger slidable within said slide, said slide having an intake opening adapted to register with said inlet and an outlet slot adapted to register with either of said outlets, said plunger being adapted to receive an article of material and having also a slot in its bottom adapted to register with said outlet slot, a block slidably mounted on said body over said slide, a follower under pressure in said block and adapted to extend into the path of said slide, said follower being positioned to be moved out of the path of said slide by an article of regular length received in and moving with said plunger and slide, a wall portion formed 20 with said block between said material outlet and follower and engageable by an article of excessive length received in said plunger and slide, whereby to shift said block on further actuation of said plunger and slide, means operable on 25 shifting of said block for stopping said slide with the outlet slot thereof in register with the irregular material outlet, means for further shifting said block, and a yieldable driving connection between said plunger and slide, whereby 30 shifting of said block for stopping said slide with the outlet slot thereof in register with the irregular material outlet, means for further shifting said block, and a yieldable driving connection between said plunger and slide, whereby 35 said plunger may be moved relatively to said slide until its outlet slot registers with the outlet slot of said slide on such further shifting of said block.

8. In a mechanism for selecting articles of a given length, a body having a material inlet and two material outlets, one for regular and the other for irregular articles of manufacture, a hollow slide beneath said inlet and over said outlets, a plunger slidable within said slide, said slide having an intake opening adapted to register with said inlet and an outlet slot adapted to register with either of said outlets, said plunger being adapted to receive an article of material and having also a slot in its bottom adapted to register with said outlet slot, a block slidably mounted on said body over said slide, a follower under pressure in said block and adapted to extend into the path of said slide, said follower being adapted to be held out of the path of said slide by an article of regular length received in said plunger and slide, a wall portion formed with said block between said material outlet and follower and engageable by an article of excessive length received in said plunger and slide, whereby to shift said block on further actuation of said plunger and slide, means operable on shifting of said block for stopping said slide with the outlet slot thereof in register with the irregular material outlet, means for further shifting said block, a yieldable driving connection between said plunger and slide, whereby said plunger may be moved relatively to said slide until its outlet slot registers with the outlet slot of said slide on such further shifting of said block, and stop means between said follower and slide and operative to hold the outlet slot of said slide over the irregular material outlet when an article of insufficient length fails to move said follower.

75 9. In a mechanism for selecting articles of a

given length, a body having a material inlet and two material outlets, one for regular and the other for irregular articles of manufacture, a hollow slide beneath said inlet and over said outlets, a plunger slideable within said slide, said slide having an intake opening adapted to register with said inlet and an outlet slot adapted to register with either of said outlets, said plunger being adapted to receive an article of material and having also a slot in its bottom adapted to register with said outlet slot, a block slidably mounted on said body over said slide, a follower under pressure in said block, a wall portion formed with said block between said material outlet and follower and engageable by an article of excessive length received in said plunger and slide, whereby to shift said block on further actuation of said plunger and slide, a stop pin normally held out of the path of said slide, a cam carried by said block and adapted to project said pin into the path of said slide on shifting of said block, said pin being positioned to stop said slide with the outlet slot thereof in register with the irregular material outlet, means for further shifting said block, and a yieldable driving connection between said plunger and slide, whereby said plunger may be moved relatively to said slide until its outlet slot registers with the outlet slot of said slide on such further shifting of said block.

10. In a mechanism for selecting articles of a given length, a body having a material inlet and two material outlets, one for regular and the other for irregular articles of manufacture, a hollow slide beneath said inlet and over said outlets, a plunger slidable within said slide, said slide having an intake opening adapted to register with said inlet and an outlet slot adapted to register with either of said outlets, said plunger being adapted to receive an article of material and having also a slot in its bottom adapted to register with said outlet slot, a block slidably mounted on said body over said slide, a follower under pressure in said block, a wall portion formed with said block between said material outlet and follower and engageable by an article of excessive length received in said plunger and slide, whereby to shift said block on further actuation of said plunger and slide, a stop pin normally held out of the path of said slide, a cam carried by said block and adapted to project said pin into the path of said slide on shifting of said block, said pin being positioned to stop said slide with the outlet slot thereof in register with the irregular material outlet, means for further shifting said block, a yieldable driving connection between said plunger and slide, whereby said plunger may be moved relatively to said slide until its outlet slot registers with the outlet slot of said slide on such further shifting of said block, and stop means between said follower and slide and operative to hold the outlet slot of said slide over the irregular material outlet when an article of insufficient length fails to move said follower. 65

11. A loading device comprising a pair of dimension-testing disks, one of which is rotatable relatively to the other, said disks being axially-alined and spaced at their peripheries to receive the smaller end and retain the larger end of an acceptable tapered member and permit discharge of an unacceptable member through the space, a chute for supplying such members and having its outlet disposed at the space between said disks, and agitating means in said outlet, the 75

member-engaging faces of the disks being of small radial length and contacting the member intermediate the member ends, whereby an acceptable member will be advanced solely by contact of its periphery with said faces with the member free to swing on its points of engagement with the faces during the advance.

12. A loading device comprising a pair of dimension-testing disks, one of which is rotatable relatively to the other, said disks being axially-aligned and spaced at their peripheries to receive the smaller end and retain the larger end of an acceptable tapered member and permit discharge of an unacceptable member through the space, a chute for supplying such members and having its outlet disposed at the space between said disks, agitating means in said outlet, and a cam carried by the rotatable disk for actuating said means the member-engaging faces of the disks being of small radial length and contacting the member intermediate the member ends, whereby an acceptable member will be advanced solely by contact of its periphery with said faces with the member free to swing on its points of engagement with the faces during the advance.

13. A loading device comprising a pair of dimension-testing disks, one of which is rotatable, said disks being spaced at their peripheries to receive the smaller end and retain the larger end of an acceptable tapered member and permit discharge of an unacceptable member through the space, a chute for supplying such members and having its outlet disposed at the space between said disks, a delivery chute extending from said space, and tripping means at the inlet of said delivery chute and engageable by an end of said members for laying said members uniformly coaxial with said delivery chute.

14. A loading device comprising a pair of dimension-testing disks, one of which is rotatable relatively to the other, said disks being axially-aligned and spaced at their peripheries to receive the smaller end and retain the larger end of an acceptable tapered member and permit discharge of an unacceptable member through the space, a chute for supplying such members and having its outlet disposed at the space between said disks, means for delivering said members to said chute, and means carried by said rotatable disk for actuating said means, the member-engaging faces of the disks being of small radial length and contacting the member intermediate the member ends, whereby an acceptable member will be advanced solely by contact of its periphery with said faces with the member free to swing on its points of engagement with the faces during the advance.

15. A loading device comprising a pair of dimension-testing disks, one of which is rotatable, said disks being spaced at their peripheries to receive the smaller end and retain the larger end of an acceptable tapered member and permit discharge of an unacceptable member through the space, a chute for supplying such members and having its outlet disposed at the space between said disks, agitating means in said outlet, means for delivering said members to said chute, and means carried by said rotatable disk for actuating said means and operating said agitating means.

16. A loading device comprising a pair of dimension-testing disks, one of which is rotatable, said disks being spaced at their peripheries to receive the smaller end and retain the larger end of an acceptable tapered member and permit dis-

charge of an unacceptable member through the spaces, a chute for supplying such members and having its outlet disposed at the space between said disks, agitating means in said outlet, means for delivering said members to said chute, and a cam carried by said rotatable disk for actuating said means and operating said agitating means.

17. A loading device comprising a pair of disks, one of which is rotatable, said disks being spaced at their peripheries to receive the smaller end and retain the larger end of a tapered member, a chute for supplying such members and having its outlet disposed at the space between said disks, a delivery chute extending from said space, means for delivering said members to the first named chute, means carried by the rotatable disk for actuating said means, and means engageable by members accumulated in the delivery chute for holding the first named means out of the path of the second named means.

18. A loading device comprising a pair of disks, one of which is rotatable, said disks being spaced at their peripheries to receive the smaller end and retain the larger end of a tapered member, a chute for supplying such members and having its outlet disposed at the space between said disks, a delivery chute extending from said space, means for delivering said members to the first named chute, means carried by the rotatable disk for actuating said means, a bell crank lever carried by the first named means and adapted to enter the delivery chute on actuation of said means, said lever being engageable by members accumulated in the delivery chute for holding the first named means out of the path of the second named means.

19. A loading device comprising a pair of disks, one of which is rotatable, said disks being spaced at their peripheries to receive the smaller end and retain the larger end of a tapered member, a chute for supplying such members and having its outlet disposed at the space between said disks, a finger pivotally mounted adjacent the outlet of said chute and adapted to enter said outlet, a spring tending to draw said finger into said outlet, and means carried by said rotatable disk for periodically tensioning and releasing said spring.

20. A loading device comprising a pair of disks, one of which is rotatable, said disks being spaced at their peripheries to receive the smaller end and retain the larger end of a tapered member, a chute for supplying such members and having its outlet disposed at the space between said disks, a finger pivotally mounted adjacent the outlet of said chute and adapted to enter said outlet, a lever fixed to said finger, a spring connecting said lever to said chute and tending to draw said finger into said outlet, and a cam carried by said rotatable disk and engageable with said lever for periodically tensioning and releasing said spring.

21. In assorting mechanism for elongated tapered objects and wherein the objects are assorted dimensionally into accepted and rejected classes, means for establishing a travel path through which the objects travel individually, means for delivering objects to the travel path in endwise direction, individual stations in such path for successively testing the length and diameter dimensions of each object relative to predetermined standards of such dimensions, the travel path to and from said stations being operative to maintain the object constantly in such endwise direction during object advance, each

station having means for moving the object in the path transversely of the direction of length of the object and for applying the test during such transverse movement, and outlet from the path 5 at each station and to which the testing means delivers rejected objects, and means active in the path for causing successively-tested accepted objects to be delivered from the path with similar ends of the objects as the advance end.

10 22. In assorting mechanism for elongated tapered objects and wherein the objects are assorted dimensionally into accepted and rejected classes, means for establishing a travel path through which the objects travel individually, 15 means for delivering objects to the travel path in endwise direction, individual stations in such path for successively testing the length and diameter dimensions of each object relative to predetermined standards of such dimensions, the 20 travel path to and from said stations being operative to maintain the object constantly in such endwise direction during object advance, each station having means for moving the object in the path transversely of the direction of length 25 of the object and for applying the test during such transverse movement, an outlet from the path at each station and to which the testing means delivers rejected objects, the diameter-testing means including a support for accepted objects with the support active on the object solely 30 at points intermediate the ends of the object being tested.

23. In assorting mechanism for elongated tapered objects and wherein the objects are assorted dimensionally into accepted and rejected classes, means for establishing a travel path through which the objects travel individually, 35 means for delivering objects to the travel path in endwise direction, individual stations in such path for successively testing the length and diameter 40 dimensions of each object relative to predetermined standards of such dimensions, the travel path to and from said stations being operative to maintain the object constantly in such endwise direction during object advance, each station having means for moving the object in the path transversely of the direction of length of the object and for applying the test during such transverse movement, an outlet from the path at each station and 45 to which the testing means delivers rejected objects, the diameter-testing means including a support for accepted objects with the support active on the object solely at points intermediate and spaced from the ends of the object being tested.

50 24. In assorting mechanism for elongated tapered objects and wherein the objects are assorted dimensionally into accepted and rejected classes, means for establishing a travel path through which the objects travel individually, 55 means for delivering objects to the travel path in endwise direction, a length-testing station within the path, said station including means for shifting an object in the path transversely of the direction of length of the object and during the 60 transverse movement automatically determining the class to which the object belongs, an outlet from the path at such station for rejected objects, a diameter-testing station in such path for testing length-accepted objects and including 65 means for shifting such object transversely in such path and during the transverse movement automatically rejecting objects failing to meet the predetermined standard as to diameter dimension, an outlet at such station for the rejected objects, the 70 travel path to and from said stations being opera-

tive to maintain the object constantly in such endwise direction during advance, and means active in such path for causing successively-tested accepted objects to be delivered from the path with similar ends of the objects as the advance end. 5

25. In assorting mechanism for elongated tapered objects and wherein the objects are assorted dimensionally into accepted and rejected classes, means for establishing a travel path 10 through which the objects travel individually, means for delivering objects to the travel path in endwise direction, a length-testing station within the path, said station including means for shifting an object in the path transversely of the direction of length of the object and during the transverse movement automatically determining the class to which the object belongs, an outlet from the path at such station for rejected objects, a diameter-testing station in such path for testing 15 length-accepted objects and including means for shifting such object transversely in such path and during the transverse movement automatically rejecting objects failing to meet the predetermined standard as to diameter dimension, an outlet at such station for the rejected objects, the travel path to and from said stations being operative to maintain the object constantly in such endwise direction during advance, the diameter-testing means including a support for accepted 20 objects with the support active on the object solely at points intermediate and spaced from the ends of the object being tested. 25

26. Apparatus as in claim 24, characterized in that the diameter-testing means includes a support for accepted objects with the support active on the object solely at points intermediate and spaced from the ends of the object being tested. 30

27. Apparatus as in claim 24, characterized in that the length-testing means is operative on the object for testing purposes regardless of which end of the object may be in advance, and the diameter-testing means is operative on the object for testing purposes only when the object is presented with a predetermined end in advance, means being provided at the diameter-testing station for agitating untested objects to cause proper presentation thereof. 45

28. Apparatus as in claim 24, characterized in that the length-testing means is operative on the object for testing purposes regardless of which end of the object may be in advance, and the diameter-testing means is operative on the object for testing purposes only when the object is presented with the smaller end in advance, means being provided at the diameter-testing station for agitating untested objects to cause proper presentation thereof. 55

29. Apparatus as in claim 24, characterized in that the length-testing means is operative on the object for testing purposes regardless of which end of the object may be in advance, and the diameter-testing means is operative on the object for testing purposes only when the object is presented with the smaller end in advance, said latter means being operative to temporarily reject objects presented with the larger end in advance, means being provided at the diameter-testing station for agitating untested objects to cause proper presentation thereof. 65

30. Apparatus as in claim 24, characterized in that the length-testing means is operative on the object for testing purposes regardless of which end of the object may be in advance, and the diameter-testing means is operative on the object 70

75

for testing purposes only when the object is presented with the smaller end in advance, said latter means being operative to temporarily reject objects presented with the larger end in advance, 5 means being provided for turning the temporarily rejected objects end for end and again presenting them for testing.

31. Apparatus as in claim 24, characterized in that the diameter-testing means includes a support for accepted objects with the support active on the object solely at points intermediate and spaced from the ends of the object being tested, said support being operative to temporarily reject objects presented with the larger 10 end in advance, means being provided for turning the temporarily rejected objects end for end and again present them for testing, whereby the objects undergoing diameter test will be tested under similar conditions.

32. In assorting mechanism for elongated tapered objects and wherein the objects are assorted dimensionally into accepted and rejected classes, means for establishing a travel path through which the objects travel individually and 15 normally in endwise direction, a length-testing station within the path, said station including means for shifting an object transversely in such path and during the transverse movement automatically determining the class to which the 20 object belongs, an outlet from the path at such station for rejected objects, a diameter-testing station in such path for testing length-accepted objects and including means for shifting such object transversely in such path and during the 25 transverse movement automatically rejecting objects failing to meet the predetermined standard as to diameter dimension, an outlet at such station for the rejected objects, and means active in such path for causing successively-tested accepted objects to be delivered from the path 30 with similar ends of the objects as the advance end, control means being provided to temporarily prevent delivery of objects to the length-testing means in presence of an excess delivery of accepted objects at the delivery end of the path.

33. In assorting apparatus for elongated objects, a length-testing mechanism positioned to receive the objects individually and successively by endwise movement and to deliver the tested object by a similar movement, said mechanism being movable in directions transverse to such endwise direction of the object during the test, said mechanism including a pair of telescoped elements adapted to support the object when received and during the transverse movement, said elements being adapted to travel both in unison and relatively to each other during the test, and means rendered active by the positioned object for controlling the point in the travel of the elements where the relative movement begins, the element travel of both elements being in the same direction during the testing period.

34. Apparatus as in claim 33, characterized in that the control means includes a member normally active to limit advance of one of the elements and thereby begin the period of relative

movement of the elements, said member being movable relative to its support and so positioned that an object of standard length will move the member from its normal position to permit continued advance of the elements in unison while an object of less than standard length will be ineffective to move the member from such normal position. 5

35. Apparatus as in claim 33, characterized in that the control means includes a member normally active to limit advance of one of the elements and thereby begin the period of relative movement of the elements, said member being movable relative to its support and so positioned that an object of standard length will move the member from its normal position to permit continued advance of the elements in unison while an object of less than standard length will be ineffective to move the member from such normal position, said member and its support being bodily movable with the object in presence of an object of greater length than the standard length, the control means including a normally inactive stop for such element, said stop being adapted to be rendered active by the movement of said support. 20

36. In assorting apparatus for elongated objects, a length-testing mechanism positioned to receive the objects individually and successively by endwise movement and to deliver the tested object by a similar movement, said mechanism being movable in directions transverse to such endwise direction of the object during the test, said mechanism including a pair of telescoped elements adapted to support the object during the transverse movement, said elements being adapted to travel both in unison and relatively to each other during the test, and means rendered active by the positioned object for controlling the point in the travel of the elements where the relative movement begins, independent means being provided for limiting the length of the relative movement of the members to cause such latter movement to be of equal length regardless of the point of beginning of such movement. 40

37. In assorting apparatus for tapered objects, a diameter-testing mechanism, having an object-presenting station, means for presenting objects to said mechanism at such station, said members including two members having faces spaced apart a distance greater than the smaller diameter end of the object and less than the point of greatest diameter of the object, said members being movable relative to each other in the direction of length of the faces, whereby objects of standard diameter dimension will be solely supported and transported by such faces with the support active intermediate the ends of the object when said objects are presented with the smaller diameter end in advance and will reject objects presented with the greater diameter portion presented in advance, and means operative in the presenting station for inverting such presentation-rejected objects and again presenting them with the smaller end in advance. 45
